CHARLES CAREY MANKER, OF PITTSBURGH, PENNSYLVANIA, ASSIGNOR, BY DIRECT AND MESNE ASSIGNMENTS, TO MORLEY-MANKER COMPANY, INCORPORATED, OF DOVER, DELAWARE, A CORPORATION OF DELAWARE.

VAPORIZER FOR HEAVY OILS.

1,344,423.

Specification of Letters Patent. Patented June 22, 1920.

Application filed August 16, 1917, Serial No. 186,589. Renewed May 19, 1920. Serial No. 382,687.

To all whom it may concern:

Be it known that I, CHARLES CAREY MANKER, a citizen of the United States, and a resident of Pittsburgh, in the county of Allegheny and State of Pennsylvania, have made certain new and useful Improvements in Vaporizers for Heavy Oils, of which the following is a specification.

My invention relates to improvements in devices for vaporizing hydrocarbon oils such as kerosene and the like, and it consists in the combinations, constructions and arrangements herein described and claimed.

An object of my invention is to provide a device which will vaporize hydrocarbon oils and which may be placed on an automobile to furnish the motive fluid for the same.

A further object of my invention is to provide a heating device for vaporizing hydrocarbon oils by means of the heat of the exhaust gases coming from the internal combustion engine of the automobile, with means for automatically regulating the heat and hence the quantity of the vaporized products.

A further object of my invention is to provide a device of the type described in which the oil is rapidly and efficiently vaporized and mixed with steam, the steam serving a double function, a portion of it uniting chemically with the oil vapor to produce gas and a portion serving to form a means for eliminating carbon deposits from the interior of the engine.

Other objects and advantages will appear in the following specification, and the novel features of the invention will be particularly pointed out in the appended claims.

My invention is illustrated in the accompanying drawings forming part of this application, in which—

Figure 1 is a longitudinal section through the gas diaphragm.

Fig. 2 is a section along the line 2—2 of Fig. 1.

Fig. 3 is an end view of the device shown in Fig. 1, the head being removed.

In carrying out my invention I provide a cylindrical casing 1, which is closed at one end. This casing is covered on the outside with some heat insulating covering 2 such as asbestos sheeting or the like. The

cylindrical casing 1, is provided with an annular passageway 3, somewhat similar to the water jacket of an internal combustion engine. The passageway 3 communicates at one end with a threaded opening 4, into which the end of the exhaust pipe 5 extends.

The opposite end of the cylindrical casing 1 is provided with an annular flange 1^x arranged to receive a cylindrical closure plate 6, suitable packing material 7 being disposed between the plate and the flange. In order to hold this closure plate 6 in position I may provide screws 8.

The casing 1 has a flange 1^y which extends outwardly beyond the edge of the casing and also forwardly, that is to say, in the direction parallel to the axis of the cylinder. A head 9 is secured to this flange by means of bolts 10, suitable packing 11 being interposed between the head and flange. The head is provided with a centrally threaded opening 12 arranged to receive a hollow screw plug 13, which is designed to bear on the closure plate 6 so as to form an additional holding means for the latter. This screw plug is provided with openings 13^a. The construction described forms a passage 14 between the head and the end of the casing which passage communicates with the passage 3.

On the interior of the cylindrical casing 1 is an expansion tube 15, which is made of copper or other material having a high coefficient of expansion. One end of this tube is fixed in the closed end of the cylinder. The other end is provided with a laterally extending arm 16 which is pivoted at 17^x to a lever 18. The fulcrum of the lever 18 is at 19 on a bracket 20 formed integrally with the casing 1. A rod 17 having a relatively low co-efficient of expansion such as a carbon rod is slidably disposed within the tube 15. One end of this rod bears against the lever 18 in a recess 21. The other end of the rod is secured to a valve 22 which is arranged to open and close the threaded opening 4.

Surrounding the expansion tube 15 is a tube 18, one end of this tube being supported by a flange 15^x on the tube 15 and the other being secured to a perforated plate 23.

The casing 1 is provided with a number

of openings extending from the exterior to the interior, these openings being shown at 24, 25, 26 and 27. A valve casing which I have denoted in general by V, has a threaded portion 28, which extends into the opening 24, for holding the valve casing in position. In Fig. 2, I have shown the detail construction of this portion of the device. It will be seen, that it comprises a body portion 29 having a cap 30 which is held to the body portion by means of bolts 31 and a diaphragm 32 is disposed between the cap and the body portion and is normally under the tension of a spiral spring 33. Secured 10 to the under-side of the diaphragm is a slidale valve 34 which is designed to control the flow of oil from an inlet pipe 35 on one side and the flow of water from the inlet pipe 36 on the other side. To this end, 15 the valve is provided with passageways 37 on the sides thereof. The valve has a central longitudinal passageway 38 which affords communication between the interior of the casing 1 and the space 39 above the diaphragm 32.

The openings 25 and 26 may be closed by screw plugs 25^x and 26^x respectively. The opening 27 communicates with a pipe 40. The oil enters the pipe 35. The water enters into the pipe 36.

The engine is started by any ordinary means such as by an auxiliary gasoline feeding device, not shown. The heated gases from the exhaust pass through the pipe 5 and in through the space or passageway 3, thence through the passageway 14 out through the pipe 14^x. The heat from the exhaust gases is transmitted to a number of metal balls 45, disposed on the interior of 35 the cylindrical casing, the purpose of these balls being to rapidly absorb and to rapidly radiate the heat. The spring 33 holds the valve 34 open so that oil and water are fed into the interior of the cylinder upon the 40 heated balls 45. The heated oil and water vaporizes and form the gas. This gas passes out through the pipe 40 to the mixer 41 and thence into the cylinder of the engine. The 45 gas is laden with steam which tends to keep down the carbon in the cylinder and to prevent its formation.

Now when the pressure of the gas within the gas producer rises to a given amount, say from one to three pounds, this pressure 55 is transmitted to the space 39 above the diaphragm and causes the valve 34 to close thus shutting off the flow of oil and water. The oil and water which has entered the cylinder is formed into a gas which is used as it is 60 needed and when the pressure is reduced to a given amount, due to the using up of the gas, then the spring 33 will open the valve 34 and again permit the feeding of the oil and water into the interior of the cylinder.

65 In the drawings I have shown pipes 35

and 36 as leading directly from the receivers, but it is obvious that these pipes may have control valves located in any suitable place so as to shut off the flow when the engine is not running.

When the temperature of the cylinder and the balls contained therein rises above a certain point, then the thermostatic member operates to close the valve 22 thus shutting off the flow of the exhaust gases through the 70 passage 3 and allowing the cylinder to cool down. When it has cooled down to a pre-determined temperature, then the valve 22 is permitted to open under pressure of the exhausted gases by the contraction of the 75 thermostatic element 15. It will be observed that the copper tube is the main expansion member. The arrangement is such that when the tube expands a given distance the valve is opened a correspondingly greater 80 distance due to the fact that the movement of the tube is multiplied through the lever connection with the rod 17 upon which the valve is located. This multiplication of the 85 elongation of the tube is effected without a 90 correspondingly greater increase in space.

The device as described may be used for heavier hydrocarbon oils and the automatic operation of the device permits its use on automobiles whose owners have little or no 95 knowledge of mechanics. The device requires very little attention and is not easily liable to get out of order.

I claim:

1. In a vaporizer for heavy oils, a casing 100 having an inlet and an outlet, a valve for controlling said inlet, a slidale rod secured to said valve, an expansion tube surrounding said rod and having an arm, the end of the expansion tube near the valve being rigidly secured in position, a lever pivotally mounted on the opposite end of the casing and having a pivotal connection with the arm at one end, and being in engagement with the rod at the other end.

2. In a vaporizer for heavy oils, a cylinder 105 having an inlet and an outlet, a valve for controlling the inlet, a slidale rod secured at one end to said valve, an expansion tube surrounding the said rod, said expansion tube being rigidly secured to the casing near the inlet, the opposite end of the rod being provided with a laterally extending arm, a lever pivotally mounted on the casing at the opposite end from the inlet and having a 110 pivotal attachment to said arm, the opposite end of the lever having a recess arranged to receive the end of said slidale rod.

3. In a vaporizer for heavy oils, a cylindrical casing having a passage in its walls 125 for the products of combustion, said casing having an inlet and an outlet, a valve for controlling said inlet, a slidale rod disposed centrally with respect to the casing and being connected to said valve, an expansion 130

tube surrounding said slidable rod and forming a bearing therefor, the end of the expansion tube nearest the valve being secured to the end of the cylinder, the opposite end 5 of the expansion tube having a laterally extending arm, a lever pivotally mounted on the end of the casing opposite the inlet and having a recess disposed in alinement with the central axis of the slidable rod and arranged to receive one end of the rod, and 10 a second tube surrounding said expansion tube, said second tube being rigidly secured to the cylinder.

CHARLES CAREY MANKER.
